UNITED STATES PATENT OFFICE.

CHARLES HOMEWOOD, OF WATERLOO, IOWA.

SWIMMING APPARATUS.

1,128,682.

Specification of Letters Patent. Patented Feb. 16, 1915.

Application filed October 13, 1914. Serial No. 866,424.

To all whom it may concern:

Be it known that I, CHARLES HOMEWOOD, a citizen of the United States of America, and a resident of Waterloo, Blackhawk 5 county, Iowa, have invented certain new and useful Improvements in Swimming Apparatus, of which the following is a specification.

My invention relates to improvements in 10 swimming apparatus, and the object of my improvement is to provide an aid for swimmers' use, being the provision of flexible pockets adapted to be mounted upon the limbs of the swimmer, said pockets adapted 15 to collapse when the limbs are to be moved forwardly, and to open out and engage the water when the limbs are moved against the water to propel the body. This object I have accomplished by the means which 20 are hereinafter described and claimed, and which are illustrated in the accompanying drawings, in which:

Figure 1 is a view of the outer side of an arm on which my improved swimming 25 pockets are mounted, and Fig. 2 is the view of the opposite side of said arm, showing similar pockets mounted thereon. Fig. 3 is a view of one side of a leg with similar pockets mounted thereon, and Fig. 4 is a 30 view of the opposite side of said leg, with like pockets mounted thereon. Figs. 5 and 6 are enlarged views of said pockets, showing them respectively in the closed and open positions. Fig. 7 is a transverse section 35 of a sleeve and the pockets on opposite sides thereof. Fig. 8 is a perspective view of a part of a sleeve having a plurality of pockets mounted therealong, said pockets being arranged to pass completely around the 40 sleeve. Fig. 9 is a transverse section of the sleeve and one of the pockets shown in said Fig. 8.

Similar numerals of reference denote corresponding parts throughout the several 45 views.

I am aware that solid paddle-shaped bodies have been hinged in alinement along fixed supports adapted to be mounted upon the limbs of a swimmer for use in facilitating swimming. It is obvious, however, that such appliances are very cumbersome, inconvenient in use, and very apt to get out of order, and are also extremely liable to 50 get caught in clothing or objects which may

be situated in the water, such as vegetation, 55 branches, or other obstructions.

My invention is designed to obviate all these inconveniences.

The numeral 2 denotes an elastic sleeve, 60 which may be an armlet, as shown in Figs. 1 and 2, or a legging as shown in Figs. 3 and 4. The open ends of the sleeve may be thickened, as shown, to strengthen them at these places, and prevent the detaching thereof from the limb. On opposite sides 65 of both the armlet 2 and the legging 5, are arranged rows of pockets 1, preferably of progressively decreasing sizes in the direction extending from the wider to the narrower ends of the same. The pockets are 70 preferably cut of triangular shape and attached to the sleeve in such a manner, as to open obliquely to one side thereof. However, the pockets may open differently, but it is requisite that they should open in a 75 direction somewhat rearwardly in the line of movement.

Since the movements of the limbs in swimming are largely sidewise as well as rearwardly, it is better to have the pockets open 80 obliquely as shown, in order to better engage the water on the power strokes. When the swimmer is progressing forwardly and thrusts out the arms forwardly, the pockets collapse flatly as shown in Fig. 5, and offer 85 no opposition to progress through the water. When the limbs are thrust back the pockets open out into the position shown in said Fig. 6, and thus engage the water most efficiently 90 in aiding the swimmer in his forward movement. The sleeve shown in said Figs. 8 and 9, has the pockets so cut and arranged as to completely extend around the sleeve, and are attached thereto at one longitudinal edge and may open downwardly, when on the leg 95 sleeve 5, and a part thereof will lie close to the sleeve under the action of gravity when the sleeve is horizontal. Since the pocket is of so large an extent, in order to prevent its becoming inverted, I connect a short flexible 100 cord 4 between the middle part of its free edge and the sleeve. This cord not only prevents inversion of the pockets, but also prevents its sticking fast to the sleeve while holding it out a little way therefrom, so that 105 water may enter therebetween. The pockets 3 may also be cut obliquely to the length of the sleeve as desired, and the pockets may be

otherwise arranged upon the sleeve than is shown, and may be made of a different form, without departing from the principle of my invention. Preferably, both the sleeve and the pockets thereon are made from soft india rubber, flexible and elastic.

A loop 6 may be attached to one end of the legging 5 to pass about the foot, in order to retain the legging in place.

10 Having described my invention, what I claim as new, and desire to secure by Letters Patent, is:

1. A swimming apparatus, comprising a plurality of pockets, arranged obliquely to open sidewise angularly to the limb of the person on which they are mounted.

15 2. A swimming apparatus, comprising a plurality of elastic pockets arranged to open obliquely to one side of the limb of the wearer, and a sleeve on which said pockets are mounted.

20 3. A swimming apparatus, comprising an elastic sleeve, a plurality of obliquely opening elastic pockets mounted thereon, and means for preventing the inverting of the pockets.

25 4. A swimming apparatus, comprising an elastic sleeve, and flexible obliquely opening pockets mounted on opposite sides thereof.

30 5. A swimming apparatus, comprising an elastic sleeve, a flexible pocket mounted thereon to open obliquely relative thereto, and a cord connecting the open end of the pocket with the sleeve.

35 6. A swimming apparatus, comprising an elastic sleeve, a plurality of alined pockets

thereon opening in the same direction and obliquely relative to said sleeve and each extending completely about the sleeve.

7. A swimming device, comprising a pocket adapted to be detachably secured obliquely to a limb of the wearer, and opening against the water during the side power-stroke of said limb.

8. A swimming device, comprising a 4. sleeve, and a flexible pocket thereon, the pocket being flexed and secured to the sleeve along lines meeting at an angle to open obliquely relatively to the length of the sleeve. 50

9. A swimming device, comprising a sleeve, and a plurality of flexible pockets thereon, each pocket being flexed and secured to the sleeve along diverging lines to cause the pocket to open obliquely relatively to the length of the sleeve. 55

10. A swimming device, comprising a sleeve, and a plurality of flexible pockets alined theralong and opening in the same direction, each pocket being flexed and secured to the sleeve along diverging lines to cause the pocket to open obliquely relatively to the length of the sleeve, and the successive pockets being partially overlapped over the ones adjacent thereto. 60 6

Signed at Waterloo, Iowa, this 26th day of Sept., 1914.

CHARLES HOMEWOOD.
